UNITED STATES PATENT OFFICE.

WALTER M. SCHWARTZ AND HARRY COULSTON, OF PHILADELPHIA, PENNSYLVANIA,
ASSIGNEES TO THE PHILADELPHIA TEXTILE MACHINERY COMPANY, OF PHILA-
DELPHIA, PENNSYLVANIA, A CORPORATION OF PENNSYLVANIA.

STOCKING-DRIER.

1,112,329.

Specification of Letters Patent. Patented Sept. 29, 1914.

Application filed May 17, 1913, Serial No. 768,272. Renewed February 24, 1914. Serial No. 820,660.

To all whom it may concern:

Be it known that we, WALTER M. SCHWARTZ and HARRY COULSTON, citizens of the United States, residing in Philadelphia, county of Philadelphia, State of Pennsylvania, have invented certain Improvements in Stocking-Driers, of which the following is a specification.

Our invention relates to driers for drying stockings and other fabrics which have to be dried on forms or boards.

The invention also relates to certain improvements in driers in which carriers are traversed in an endless path and the stocking or other forms are mounted on the carrier. During a portion of the travel, the forms pass through a drying chamber in which hot air is circulated. The broad idea is fully set forth and claimed in the patent granted to Albert Gee, December 10th, 1912, and numbered 1,047,039.

One object of the invention is to construct the drier so that the carriers do not travel through the drier.

25 A further object of the invention is to construct the drier so that comparatively small space will be occupied.

A still further object of the invention is to construct the driving mechanism so that 30 it will circulate the air and will traverse the stocking forms through the drier.

The invention also relates to details of construction described hereafter.

In the accompanying drawings: Figure 1, 35 is a front view of our improved stocking drier; Fig. 2, is a plan view; Fig. 3, is an end view; Fig. 4, is an enlarged sectional view on the line *a-a*, Fig. 1; Fig. 5, is a view looking in the direction of the arrow 40 *b*; Fig. 5¹, is a view of a detail of Fig. 5; Fig. 6, is a plan view on the line *c-c*. Fig. 1; Fig. 7, is a sectional view on the line *d-d*. Fig. 2; and Fig. 8, is a detached perspective view of a portion of one 45 of the forms and its clamp.

Referring to the drawings, 1 is a bed having an open center in the present instance, and having a quadrangular guideway 2 therein. This bed is considerably longer 50 than it is wide.

3 is the casing of the drier, recessed at the front to allow the portion 4 of the drier to overhang the rear portion of the bed. Within the drier is a partition 5, offset at 55 its upper end, and in the offset portion is an

opening 6. In an opening 7 in the partition is a rotary fan 8 of the ordinary construction, mounted on a horizontal shaft 9 which is the driving shaft of the drier in the present instance, so that when the fan 80 shaft is driven it circulates the air in the direction of the arrows around the partition 5. The upper portion of the drier is rounded so that there is no obstruction for the free circulation of the air, except where 65 it passes through the openings in the partition.

In order to heat the air as it circulates in the drying chamber, we mount a series 70 of steam coils 10 in the chamber and support them by a frame 11 which is secured to the angle plate 12 to which the upper end of the partition 5 is attached, and the lower end of this frame is secured to the front wall of the drying chamber, as illustrated in 75 Fig. 4. Cross bars 13 support the pipes, as clearly shown in said figure. The steam coil 10 is connected to a steam supply pipe 18, and 19 is a gage connected to the pipe so that the amount of pressure can be readily 80 ascertained and the steam controlled accordingly. At each end of the drier are doors 14 which are hinged, as shown, and between the doors and the front wall 15 of the drier are slots 16 and 17 of a width 85 which allow the passage of a stocking form with a stocking thereon.

Arranged to travel in the guideway 2 are carriers 20, and pivoted on the head 21 of each carrier is a bracket 22 having a spindle arranged to extend through the bearing on the head 21. On the outer end of this spindle is an arm 23 having two rollers 24 and 25. The roller 24 is adapted to a rail 26 secured to the table and running 90 parallel with the guideway at the back and at one side of the bed, as clearly shown in Fig. 2. This roller also travels on a right angled rail 27 extending parallel with the guideway at the front of the table and at 100 the opposite end, as clearly illustrated in said figure. The other roller 25 travels over a cam plate 28, when the stocking form emerges from the drier and is lowered by this cam plate, in the present instance to 105 the horizontal position to allow for the removal of a stocking from the form; the form resting on the support 29 during this operation. The stockings may be removed from the forms by hand or by automatic 110

means. In this application we have not shown any automatic means for removing a stocking from a form, but said automatic means is fully set forth and claimed in a companion application filed on the 14th day of May, 1913, under Serial No. 767,649.

It will be understood that the stocking can be removed from the form by hand after the form has been turned to the horizontal position, and when it is desired to remove a stocking without turning the form, the roller 25, cam plate 28 and support 29 can be dispensed with.

In the present instance the stocking form 30 is made of metal, but it will be understood that it may be made of wood, or other material, without departing from the essential features of the invention. The form is detachably secured to a clamp head 31 having a spindle 32 which extends at an angle through a bearing in the bracket 22. A counterweight 33 is used to hold the form 30 in an upright position, but this counterweight is only used when the form is so pivoted to the carrier that it can be moved from the vertical to the horizontal position. The spindle 32 is narrow and extends through a slot 34 on the bottom plate 35 of the overhanging portion 4 of the drier, so that comparatively little hot air escapes through the slot. By this construction the mechanism of the carrier which requires lubrication is on the outside of the drier and is not subjected directly to the circulating hot air.

The carriers are traversed in the guideways in the present instance, by mechanism broadly set forth and claimed in a patent granted to us on February 25th, 1913, No. 1,054,459, and this mechanism is slightly modified to accommodate the particular construction of this machine. This construction we will now proceed to describe.

The fan shaft 9 is the driving shaft in the present instance, and has a cone pulley 36 at one end around which passes a belt 37 which also passes around a cone pulley 38 on a stud 39.

40 is a shifter rod mounted in bearings 41 in a bracket depending from a frame 42, and this shifter rod has a forked arm 43 engaging the belt 37. The stud 39 is mounted on an arm 44, adjustable on the frame 42, so that, by turning the arm on the frame, 55 the slack of the belt can be taken up. On the hub of the cone pulley 38 is a gear wheel 45 meshing with a gear wheel 46 on a shaft 47 mounted in the frame 42, and on this shaft is a worm 48 which meshes with a 60 worm wheel 49 loosely mounted on the shaft 50. On the hub of this worm wheel and arranged to slide on the shaft 50 is a clutch sleeve 51 controlled by an arm 52 pivotally mounted on the frame and actuated by a 65 rod 53 extending to one side of the machine

in the present instance, so that the shaft can be thrown into and out of gear by the said rod 53.

67 is a treadle shaft mounted on the floor in the present instance, and on this shaft 70 is an arm 68 which engages the rod 53, so that, if desired, the clutch sleeve can be moved into and out of engagement with the worm wheel by actuating the treadle shaft by the foot. The shaft 50 extends along the rear of the bed and on the shaft are cams 54 and 54^a, as illustrated in Fig. 6. The cams engage a pin 55 on the underside of each carrier 20. The pins are preferably provided with rollers so that the cams will have a rolling contact with the pins. The shaft 50 is geared to the transverse shaft 56 by bevel gearing 57, Fig. 6, and is geared to the shaft 58 by bevel gearing 59.

60 is a longitudinal shaft at the front of the machine and this shaft is geared, in the present instance, to the shafts 56 and 58 by bevel gearing 61 and 62, respectively. On the shaft 60 is a cam 63 which traverses the carriers through the guideway at the front of the machine. During a portion of the travel of the carrier, the form is removed from the stocking and during the balance of the movement another stocking is placed upon the form.

When the carrier reaches the end of the frame it leaves the cam 63 and is engaged by a cam 64 on the shaft 56 which carries the form, with the stocking thereon, through the slot 16 in the drier 3 and, after the form is entirely within the drier, it is engaged by the cam 54 which traverses it longitudinally in the drier for a certain distance and until it comes in contact with a preceding carrier, which pushes it forward in the guides until it is engaged by the cam 54^a. Thus the forms with the stockings thereon remain in the drier a given length of time, and, by allowing the carriers to come in contact with each other and to push one another through the drier, a comparatively short drier may be used for a large number of forms.

When the carrier reaches the end of the longitudinal inner guideway, a cam 65 on the shaft 58 engages the pin of the carrier and removes the stocking form from the drier through the slot 17. This cam traverses the carrier until it is again engaged by the first mentioned cam 63. This carrier is moved in a continuous path. On one end of the cam 54^a is an arrow head shaped so as to enter the space between two carriers and thus separate them, as we have found that the carriers are liable to stick together due to the lubricating oil getting on the adjoining surfaces.

66 is a cam mounted on the shaft 58 which extends parallel with a portion of the cam 65 and is for the purpose of controlling the

movement of the carrier, while the form is being turned from the vertical to the horizontal position, as the carrier has a tendency to move faster than the cam 65 at this point.

- 5 In order to change the stocking form from the horizontal to the vertical position, while traversing in the front longitudinal guideway, the end 69 of the rail 27 is so arranged that it forms an abutment for the roller 24
 10 on the arm of the bracket carrying the stocking form, so that, when the roller comes in contact with this abutment, it will turn the stocking form on its pivot and will roll onto the rail 27. A cam plate 70 is located in the
 15 path of the stocking form so that, as it is raised from the horizontal to the vertical position, one edge of the form comes in contact with this cam plate 70 and turns it on its pivot, thus the side of the stocking form will be presented to the operator as this is the
 20 best position for the operator to place a stocking on the form. The form can be freely turned on its pivot to enable the operator to see that a stocking is properly placed on the form.

In order to prevent the forms turning accidentally on their pivots while traveling through the drier, we form a lug 71 on the spindle 32 of each form, and this lug travels in the narrow slot 34, holding the forms side by side.

From the above description, it is obvious that the construction of the drier is such that, when the forms, with the stockings thereon, extend into the drying chamber, the carriers and the mechanism for driving the carriers are outside of the chamber and are protected from the heat. Furthermore, all of the mechanism is accessible.

40 The operation is as follows: The operator stands in front of the machine toward one side and, as the stocking form is raised from the horizontal to the vertical position, a stocking is placed upon the form by the operator while it moves slowly past him. The stocking form is so controlled that when it traverses the first transverse guide it will enter the drying chamber through the narrow slot 16 with the toe portion of the stocking 45 in advance, and, when the form is entirely within the drier, it is traversed longitudinally thereof until it emerges from the drier through the slot 17. Then, as the carrier traverses the other transverse guideway, the form is turned on its pivot to the horizontal position, if desired, and the stocking is removed from the form either by hand or by the automatic mechanism mentioned above. As the carrier travels in the guideway at the 50 front of the machine, the stocking form assumes a vertical position in readiness for another stocking to be placed thereon.

We claim:

1. The combination in a stocking drier, of a bed; a carrier arranged to travel thereon;

a stocking form mounted on the carrier; a drying chamber arranged to receive the stocking forms and having a portion overhanging the bed and above the carrier, said drying chamber having inlet and outlet 70 openings for the forms, and a slot in the underside of the overhanging portion connected with said openings so that, as the carrier is traversed over the bed, the form, with a stocking thereon, will travel through the 75 drying chamber.

2. The combination of a bed; a carrier; means for traversing the carrier over the bed; a stocking form mounted on the carrier and connected therewith by a spindle; a drying chamber having a portion overhanging the rear of the bed and above the carrier, said overhanging portion having a longitudinal slot in its underside and having inlet and outlet slots for the passage of the form, 80 said longitudinal slot being narrow and so located that the spindle which connects the form with the carrier will travel in the slot.

3. The combination in a stocking drier, of a casing inclosing the drying chamber and 90 having a slotted overhanging portion at one side to allow for the movement of the stocking form within the drier; a vertical partition in the casing; a transverse shaft having a fan thereon located in an opening in the 95 upper end of the partition to allow for the circulation of air around the partition; and a heating coil located in the chamber at one side of the partition for heating the air as it circulates in the drying chamber.

4. The combination of a bed; an endless guideway therein; carriers mounted in the guideway; stocking forms mounted on the carriers; shafts having cams thereon for traversing the carriers in the guideway; a 105 drying chamber located at the rear of the bed and overhanging the rear portion of the guideway, the overhanging portion having a longitudinal slot therein for the passage of the connection between the carrier 110 and its form; a driving shaft; a fan thereon for circulating the air in the chamber; means for heating the air as it circulates; and mechanism whereby the cam shafts are driven from the fan shaft.

5. The combination in a drier, of a casing; means for heating the air circulating in the casing; a bed; an endless guideway in the bed; carriers arranged to travel in the guideway; a bearing bracket on the 120 head; a clamp having a spindle mounted in the bearing; a stocking form secured to the clamp; a drying chamber having an overhanging portion extending over the rear of the bed; a longitudinal slot on the 125 underside of the overhanging portion through which the clamp spindle extends; a horizontal shaft passing through the drying chamber; a fan on said shaft by which the air in said chamber is circulated; 130

- 1 a cam shaft; a cam thereon; a worm wheel on the cam shaft; a secondary shaft; a worm thereon meshing with the worm wheel; and means for driving the secondary shaft from the fan shaft.
- 2 6. The combination in a stocking drier, of a casing; a drying chamber; means for heating the air circulating in the drying chamber; a bed having a quadrangular guideway therein; carriers arranged to travel in the guideway; a head on each carrier; a bracket pivoted to the head; a stocking form having a spindle mounted in the bracket, the drying chamber having an overhanging portion extending over the rear end of the bed and having a longitudinal slot therein through which the spindle of the form travels, said casing having a vertical slot therein at each end through which the stocking form passes into and out of the drying chamber; a horizontal fan shaft; a fan thereon for circulating the air in the chamber; a cone pulley on one end of said driving shaft; a second cone pulley; a stud on which the second cone pulley is mounted; a belt passing around both of said pulleys; means for shifting the belt; a cam shaft; a cam thereon for traversing the carriers; and gearing between the second cone pulley and the cam shaft.
- 3 7. The combination in a stocking drier, of a drying chamber; a bed in front of the drying chamber having a guideway therein; carriers mounted in the guideway; a form mounted on each carrier; a spindle connecting the form with the carrier, said heating chamber having an extension projecting over the rear end of the bed and having a slot for the spindles which connect the forms to their carriers; said casing having a vertical slot at each end through which the stocking forms pass into and out of the drying chamber; means for heating the air in the drying chamber; and means for circulating the air.
- 4 8. The combination in a stocking drier, of a drying chamber; a bed having a guideway therein; carriers arranged to travel in the guideway; a cam shaft; a cam thereon; a pin on each carrier, with which the cam engages, for traversing the carriers in the guideway; a horizontal shaft extending through the drier; a fan thereon; a cone pulley on one end of said shaft; a stud having a second cone pulley thereon; a belt passing around both cone pulleys; means for shifting the belt on the cone pulleys; a gear wheel on the second cone pulley; a worm shaft; a gear wheel thereon meshing with the first gear wheel; a worm on said
- 5 worm shaft; a worm wheel loose on the cam shaft and meshing with the worm; said worm wheel having a clutch face; a clutch arranged to slide on but turn with the cam shaft; and means for shifting the clutch.
- 6 9. The combination of a bed; a quadrangular guide therein; four cam shafts geared together and located under the bed; a cam on each shaft, a series of carriers mounted on the bed and arranged to travel in the quadrangular guideway, a pin on each carrier arranged to be engaged by the cams so that the carriers will be traversed in an endless path through the guideways; a stocking form on each carrier; a drier extending over the rear longitudinal guideway and having a longitudinal slot therein through which the connection of the stocking forms extends; and means for heating and circulating the air in the drying chamber.
- 7 10. The combination in a stocking drier, of a casing; means for heating the air in the casing; means for circulating the air; a bed having a quadrangular guideway therein; carriers mounted in the guideway; a stocking form mounted on each carrier and connected thereto by a spindle; said drying chamber having an overhanging portion extending over the rear portion of the bed and having a narrow slot at its underside in which travels the spindle connecting the carriers with the forms; four cam shafts under the bed; a cam on each cam shaft; a pin projecting from the underside of each carrier and arranged to be engaged by the cams, the cam on the rear shaft being short so that it will engage and move the carriers forward until one carrier abuts another to allow a series of forms, each with a stocking thereon, to be assembled in the drying chamber; one carrier pushing another forward until the first carrier is engaged by a cam, which traverses the carrier and its form out of the drying chamber.
- 8 11. The combination in a drier, of a bed having a quadrangular guideway; a cam shaft under the guideway; two cams spaced apart and on the shaft; carriers arranged to travel in the guideway; and pins projecting from the carriers into the path of the cams, the second cam having an arrow pointed end to separate two adjoining carriers.
- 9 In testimony whereof, we have signed our names to this specification, in the presence of two subscribing witnesses.
